VAN STORAGE ENCLOSURE

James H. Dissman, Jr., 1917 W. Mountain St., Glendale,
Calif. 91201, and William M. Bell, 17456 Mission
Blvd., Granada Hills, Calif. 91344

Filed Oct. 9, 1974, Ser. No. 513,273

Term of patent 14 years

Int. Cl. D12—16

U.S. Cl. D12—156

FIG.1

FIG.2

FIG.3

FIG.4

FIG. 1 is a perspective view of a van storage enclosure showing our new design, it being understood that the broken lines are for illustrative purposes only;

FIG. 2 is a front elevational view thereof;

FIG. 3 is a side elevational view thereof; and

FIG. 4 is a top plan view thereof.

We claim:

The ornamental design for a van storage enclosure, as shown.
